UNITED STATES PATENT OFFICE.

EARL F. BALDWIN AND FRANK E. WOODS, OF GARDNER, MASSACHUSETTS, ASSIGNEES
TO AMERICAN FIBRE CORPORATION, OF GARDNER, MASSACHUSETTS, A CORPOR-
ATION OF MASSACHUSETTS.

FOLDING AND PRESSING MECHANISM.

Application filed March 25, 1926. Serial No. 97,470.

This invention relates to mechanism for folding and pressing strip material and is particularly adapted for folding and pressing a strip of gummed or glued fiber or heavy paper to form an artificial fiber reed.

Such reed is made from heavy and tough fiber or paper, such as kraft paper, and we have found it advisable to fold and press the paper to break down the fiber along the fold lines before applying gum thereto. The paper is then unfolded and flattened, after which it is coated with gum or glue and is preferably partially dried before refolding.

Our folding and pressing mechanism is particularly well adapted for performing the refolding and repressing operation on a strip of gummed or tacky fiber or similar material. Many features of our invention are however well adapted for more general application.

It is the general object of our invention to provide folding and pressing mechanism which will fold and press strip material to excellent advantage, particularly after being coated with gum or glue.

Other features of our invention relate to arrangements and combinations of parts which will be hereinafter described and more particularly pointed out in the appended claims.

A preferred form of the invention is shown in the drawings in which

Fig. 1 is a sectional side elevation of our improved folding and pressing mechanism; Fig. 2 is a plan view of a portion of the folding mechanism;

Fig. 3 is a side elevation of a pair of folding rolls, looking in the direction of the arrow 3 in Fig. 1;

Fig. 4 is a right hand side elevation of the pressing mechanism, looking in the direction of the arrow 4 in Fig. 1;

Fig. 5 is a detail plan view looking in the direction of the arrow 5 in Fig. 1; and Figs. 6, 7 and 8 are detail views illustrating different steps in the folding and pressing operations.

Referring to the drawings, our improved folding and pressing mechanism comprises folding rolls 111 and 112 of a special construction to be described, and presser rolls 121 and 122, also of a construction especially adapted to the purposes of our invention.

The strips of fibre or paper S as they ap-

proach the folding rolls are drawn over a fixed guide-plate 110 (Fig. 1) and then pass between the folding rolls 111 and 112 mounted upon vertical studs or bearings 113 in a cross bar 114 bolted to the frame of the machine. It will be understood that a separate pair of rolls 111 and 112 is provided for each strip of fibre S. Each roll 111 is provided with a groove 115 and each roll 112 is provided with a thin flange or rib 116 extending into the groove 115 and adjacent the lower portion thereof. The rolls 111 and 112 are preferably formed of some non-corrosive metal such as brass and rotate freely upon their pivot studs 113.

As the strips S (Fig. 6) is drawn between a pair of folding rolls 111 and 112, the strip is readily refolded to the condition shown in Fig. 7, with the lower fold passing under the rib 116 and the upper and middle folds passing above the rib 116.

The folding device thus described is particularly effective in very quickly and easily refolding a fibre strip which has been previously folded, and unfolded and thereafter gummed. The folding mechanism is of such a construction that it is not easily obstructed by the gum and loose fibre which may be detached from the partially dried and sticky material as it is pulled between the rolls.

As the strips S pass from the rolls 111 and 112, they enter the grooves 120 of the lower presser roll 121, which forms a part of the pressing mechanism. One of the narrow upper presser rolls 122 is provided for each strip S and for each groove 120, and presses the folded strip firmly into the bottom of the groove to the finished form indicated in Fig. 8.

Each upper roll 122 is preferably mounted upon an anti-friction bearing 123 at the lower end of a vertically movable guide-bar 124. Each guide bar 124 is slidable in a vertical slot in a fixed cross bar 125 and is held therein by a cover plate 126.

A heavy coil spring 127 is attached to a stud 128 at the upper end of each guide-bar 124 and at its lower end is secured to the cross bar 125. The springs 127 thus act to press the upper rolls 122 firmly downward into the grooves of the lower roll 121.

A release lever 130 is pivoted to each guide-bar 124, as indicated at 131, and when

swung upward in the direction of the arrow A in Fig. 1, the cam end 132 of the lever will engage the upper face of the cross bar 125 and raise the corresponding presser roll out of its groove 120. This separation of the rolls is very desirable when it is necessary to rethread the fibre through the machine.

The rolls 121 and 122 act as feed rolls to draw the strips S through the folding rolls. The grooved roll 121 also cooperates with the upper presser rolls 122 to press the gummed layers of fiber firmly together, and furthermore acts to re-size the fiber reed, delivering a finished reed of uniform width.

As each reed leaves the bite of the pressing rolls, it is engaged by a finger 133 (Fig. 5) on a stripper plate 134 which clears the strip from the groove in the lower roll.

Our improved folding and pressing mechanism as above described has been found particularly well adapted for folding strips of material which have been coated with gum or glue and partially dried so that they are in a very sticky condition which makes them difficult to handle in the ordinary type of folding mechanism. The sticky material may be drawn between the freely rotatable folding rolls 111 and 112 without inconvenience and the different layers of the material are folded upon each other by the action of the rolls without forming such inadvertent contact between the gummed surfaces as will prevent the formation of a uniform and perfect reed.

Furthermore the grooved lower presser roll and the freely rotatable upper presser rolls are also particularly well adapted for handling the sticky material and for pressing it to an exact and uniform width.

Having thus described our invention and the advantages thereof we do not wish to be limited to the details herein disclosed otherwise than as set forth in the claims, but what we do claim is:

1. A mechanism for folding and pressing a strip of fibrous material which comprises a grooved folding roll and a flanged folding roll, the flange of the latter roll being relatively thin and projecting into the groove of the first-mentioned roll, but spaced from the walls of the groove to provide clearance for the fiber strip between said rolls.

2. A mechanism for folding and pressing a strip of gummed fiber which comprises a

grooved folding roll and a flanged folding roll, the flange of the latter roll being relatively thin and projecting into the groove of the first-mentioned roll adjacent one edge wall portion of said groove, said rolls being freely rotatable in positions closely adjacent but providing clearance for the gummed fiber between said rolls.

3. A mechanism for folding and pressing a strip of gummed fiber which comprises a grooved folding roll and a flanged folding roll, the flange of the latter roll being relatively thin and projecting into the groove of the first mentioned roll, said rolls being rotatable about adjacent parallel axes and said gummed strip being fed thereto as disposed in a plane substantially perpendicular to said axes.

4. A folding and pressing mechanism which comprises folding rolls loosely mounted on adjacent parallel axes, one of said rolls being grooved and the other of said rolls formed with a relatively thin flange projecting into the groove of the first mentioned roll, and means to draw a strip of gummed and sticky fiber between said rolls, said latter means comprising a grooved driven roll and a freely rotatable presser roll having a portion projecting into the groove of said driven roll and effective to compress the folded fiber therein to the full width of the groove.

5. A folding and pressing mechanism which comprises folding rolls loosely mounted on adjacent parallel axes, one of said rolls being grooved and the other of said rolls formed with a relatively thin flange projecting into the groove of the first mentioned roll, means to draw a strip of gummed and sticky fiber between said rolls, said latter means comprising a grooved driven roll and a freely rotatable presser roll having a portion projecting into the groove of said driven roll and effective to compress the folded fiber therein to the full width of the groove, and means for pressing said presser and driven rolls together, and additional means for manually separating said freely rotatable roll from said driven roll and for holding the separated roll in raised position.

In testimony whereof we have hereunto affixed our signatures.

EARL F. BALDWIN.
FRANK E. WOODS.
